ATTORNEY.

UNITED STATES PATENT OFFICE

SAM WESTERHEIM, OF SIOUX FALLS, SOUTH DAKOTA

WEATHER STRIP

Application filed February 20, 1929. Serial No. 341,502.

This invention relates to a weather strip particularly adaptable for use in connection with double sash windows and has for its primary object to provide, in a manner as herein-
5 after set forth, a means for sealing the air spaces between the upper sash and head of the window and between the lower sash and the window sill.

A further object of the invention is to pro-
10 vide a weather strip for the purpose afore-
said in which a pair of co-acting strips are
employed, each having a double biting en-
gagement with the portion of the window to
which it is attached.

15 A further object of the invention is to pro-
vide a weather strip as aforesaid, by means of
which air spaces at the top and bottom of the
window may be effectively closed, even though
the sash is free from contact with the sill or
20 head, thereby compensating for any shrink-
ing of the sash.

A further object of the invention is to pro-
vide a weather strip as aforesaid, by means of
25 which the lower portion of a window sash
may be effectively protected from rain or the
like, thereby eliminating the possibility of
any swelling of the bottom portion of the sash
due to saturation.

With the foregoing and other objects in
30 view, the invention consists of the novel con-
struction, combination and arrangement of
parts as hereinafter more particularly de-
scribed, and as illustrated in the accompan-
ying drawings wherein is shown a preferred
35 embodiment of the invention, but it is to be
understood that such drawings and descrip-
tion are to be taken as illustrative and that the
invention is intended to be limited only by
the scope of the claim hereunto appended.

40 In the accompanying drawings in which
like numerals are employed to designate like
parts throughout the same:

Figure 1 is a sectional view of a weather
45 strip in accordance with this invention show-
ing the adaptation thereof with the upper
sash and head of a window.

Figure 2 is an elevation of the embodiment
shown in Figure 1.

50 Figure 3 is a transverse section of the

weather strip showing the adaptation thereof
with the lower sash and sill of a window.

Figure 4 is an elevation of the embodiment
shown in Figure 3.

Figure 5 is a perspective view of the coact-
ing sections of the strip, showing the same in
disassembled relation.

Figure 6 is a sectional view of a modified
form of my invention, showing the adaptation
thereof with the upper and lower sashes of a
60 window.

Referring to the drawings in detail, with
particular reference to Figure 5, my im-
proved weather strip consists of a pair of sec-
tions 1 and 2 respectively. The section 1 com-
prises an inner member 3 of flat, elongated
formation, and an outer member 4 which ex-
tends at an acute angle from one edge of the
member 3 and the configuration of which is in
the form of a compound curve. The section 70
2 comprises an anchor portion 5 which is
semi-circular in cross section, and a resilient
grip portion 6 of ogee configuration, one
edge of which is connected to an edge of the
portion 5 by means of a neck 7. The portion 75
6 extends at an obtuse angle to the anchor por-
tion 5. The portion 5 is formed with a plu-
rality of spaced openings 8 for the passage
therethrough of suitable brads to secure the
section 2 in position. The section 1 is formed
80 with similar openings 9 at the bend between
the portions 3 and 4 for the passage of brads
or the like to secure the section 1 in position.

To apply the sections 1 and 2 to the lower
sash 10 and sill 11 of a window, as illus-
trated in Figure 3, the section 1 is disposed
with the free longitudinal edges 12 and 13
respectively of the portions 3 and 4 seating
on the sill, with the inner portion 3 extend-
ing in parallel relation to the vertical plane
of the sash. Brads 14 are then passed
through the openings 9 and driven into the
sill 11 whereby the edges 12 and 13 are drawn
into biting engagement with the upper face
95 of the sill. The spaced relation of the edges
12 and 13 and their biting engagement with
the sill provides a double stop to prevent the
passage of air or the like between the sill and
the section 1. The section 2 is secured to the
100 sash 10 by passing brads 15 through the open-

ings 8 and driving the brads into the sash, by means of which the inner face of the neck 7 is drawn tightly against the outer face of the sash and the free longitudinal edge 16 of the anchor portion 5 is drawn into biting contact with the sash. The section 2 is so spaced from the bottom of the sash 10 that when the latter is seated on the sill 11 the gripping portion 6 of the member 2 will be in engagement with the portion 4 of the section 1. The sections are formed of resilient material and the portion 6 of the section 2 is disposed at the proper inclination to have an inherent tendency to swing inwardly. 10 Thus when the gripping member 6 is brought into contact with the portion 4, the member 6 will be slightly sprung outwardly thereby drawing the sash snugly against the portion 3 and insuring a close fit between the member 6 and portion 4 as soon as they are brought into overlapping relation. When the sash is moved in a longitudinal plane away from the sill, a sliding contact is had between the portions 6 and 4, and owing to the ogee and compound curvatures of the portions 6 and 4 respectively, relatively wide bearing surfaces are provided between such portions during such sliding contact. 20

As illustrated in Figure 1, the section 1 is secured to the head 17 of the window in the same manner as to the sill 11 except that the position of the section 1 is inverted with the edges 12 and 13 thereof bearing against the lower surface of the head 17. The section 2 is secured to the upper sill 18 in the same manner as to the lower sash except that the position of the section 2 is inverted. 30

In the modification illustrated in Fig. 6, I employ a pair of sections 19 and 20 respectively. The section 19 consists of an anchor portion 21, a resilient grip portion 22, and a flat neck portion 23 connecting the anchor and grip portions 21 and 22. The anchor portion 21 is semi-circular in cross section and suitably apertured for the passage of holdfast devices 24 for securing the section to the lower face of the upper sash 18 of a window. With the holdfast devices 24 in place, the neck portion 23 is pressed flatly against the sash 18 and the free edge 25 of the anchor portion 21 is drawn into biting engagement therewith. The grip portion 22 is of curved formation and extends at an inclination from the neck 23 with its free edge 26 disposed in proximity to the upper rail of the lower sash 10 when the sashes 10 and 18 are positioned to close the window. 40

The section 20 is substantially J shaped in cross section, having a flat anchor portion 27 secured to the lower sash 10 by means of holdfast devices 28, and further having a curved portion 29 depending from the anchor portion 27 for frictional engagement with the grip portion 22 of the section 19. The free edge 20 of the depending portion 29 is di-

rected toward the lower face of the upper rail of the lower sash 10 and is driven in any suitable manner into biting contact therewith, preferably before the application of the holdfast devices 28. The resilient grip portion 22 has an inherent tendency to spring toward the depending portion 29 of the section 20 whereby the portions 22 and 29 may be effectively sealed to prevent the passage of air and the like therebetween as soon as such portions are brought into contact, even though the sashes 10 and 18 are not in their extreme closed positions. 50

It is thought that the many advantages of a weather strip in accordance with this invention may be readily apparent, and although the preferred embodiments are as illustrated and described, yet it is to be understood that changes in the details of construction may be made, which fall within the scope of the invention as defined in the appended claim. 80

What I claim is:

In a weather strip for a sliding sash type window, a section for connection with the sill of the window, and a section for connection with the sash of the window and having a resilient portion extending at an angle from the sash and snugly engaging the outer face of the section connected with the sill when the sash is closed, said resilient portion having an inherent tendency to spring inwardly and being forced outwardly when the sash is closed whereby the sash is drawn snugly against the section connected with the sill when the sash is closed and whereby a sliding engagement is had between the sections when the sash is moved in a longitudinal plane away from the sill. 90

In testimony whereof, I affix my signature hereto. 100
